(57) **CLAIM**

The ornamental design for housing for a jack, as shown and
described.

DESCRIPTION

FIG. 1 is a front perspective view of a housing for a jack in
accordance with the present design.

FIG. 2 is a left side view of the housing of FIG. 1.

FIG. 3 is a front view of the housing of FIG. 1.

FIG. 4 is a right side view of the housing of FIG. 1.

FIG. 5 is a rear view of the housing of FIG. 1.

FIG. 6 is a top view of the housing of FIG. 1; and,

FIG. 7 is a bottom view of the housing of FIG. 1.

The broken lines shown in the figures are included for the
purpose of illustrating portions of the housing for a jack and
form no part of the claimed design.

1 Claim, 6 Drawing Sheets
